UNITED STATES PATENT OFFICE.

FRANS D. FRANSON, OF OAKLAND, CALIFORNIA.

WRENCH.

Application filed November 21, 1922. Serial No. 602,486.

My invention relates to the type of wrenches in which one of the jaws may be locked in any desired position with respect to the other jaw and released to slide freely relative thereto.

An object of the invention is to provide a wrench of the character described in which the jaws may be held in any desired position with a firmness practically equal to that of a solid wrench.

Another object of the invention is to provide a wrench of the character described in which the movable jaw is normally maintained in locked position and may be released instantly and completely to allow of its unrestricted sliding movement.

A further object of the invention is to provide a wrench of the character described which can be manufactured at a cost not exceeding that of the common screw-operated type of wrench.

The invention possesses other objects and features of advantage, some of which, with the foregoing, will be set forth in the following description of the preferred form of my invention which is illustrated in the drawings accompanying and forming part of the specifications. It is understood that I do not limit myself to the showing made by said drawings and description, as I may adopt variations of the preferred form within the scope of my invention as set forth in the claims.

Referring to said drawings:

Figure 1 is a rear elevation of one form of the wrench.

Figure 2 is a side elevation of the wrench shown in Figure 1, the movable jaw of the wrench being shown in section.

Figure 3 is a transverse section taken through the movable jaw of the wrench.

As illustrated in Figure 2, the wrench comprises a fixed jaw member 5 which includes the jaw 7 and shank or lever 8 preferably formed rectangular in transverse section. Slidably mounted on said shank is a movable jaw member 9 provided with a jaw 10 and having a main opening 12 in which said shank engages. Engaging in the opening 12 and interposed between the forward side 13 of the shank and the inclined inner face 14 of the member 9 is a wedge 16 which is normally held in firm contact with the side 13 and face 14 by means of the spring 17.

As here shown the spring is seated on an ex-

tension 18 formed on the member 9 and presses against the end 19 of the wedge.

The rear side 21 of the shank is serrated or fluted, the serrations being disposed transversely of the shank. Formed in the side 22 of the opening which faces side 21 of the shank are similar serrations. In this manner with the wedge firmly held in position the serrated sides 21 and 22 of the respective members will engage each other and thereby lock the jaws against any relative movement. The serrations are formed extremely fine and close to each other. In this manner the movable jaw member may be locked practically in any position with respect to the fixed jaw.

Means are provided for drawing the wedge backward so that the member 9 may be released and permitted to slide freely on the shank so as to change its position relative the jaw 7. As here illustrated, said means comprises a lever 29 which is pivoted to the member 9 and connected to the wedge by means of a link 31. With this construction, to release the wedge it is merely necessary to press the lever inwardly thereby forcing the wedge backwardly against the resistance of spring 17, thus releasing the member 9 for movement relative to the shank. As soon as the member has been moved to the desired position the lever may be released and the wedge will automatically return to its normal position, thereby instantly locking the jaws in position.

While I have shown my invention incorporated in one form of wrench, it is obvious that it may be incorporated with other types of wrenches if desired.

I claim:

1. A wrench comprising a fixed jaw member provided with a shank having a fluted side, a movable jaw member slidably mounted on said shank having a fluted inner face for engagement with said fluted side and having an inclined inner face opposing another side of said shank, a wedge fitting between and arranged to engage said inclined face and said last mentioned side, a spring bearing against said wedge and movable jaw arranged to urge said wedge inwardly between said inclined face and opposing side whereby said fluted parts will be firmly held together, a lever fulcrumed on said movable jaw, and a link connected to said lever and wedge whereby upon the rocking of said le-

ver said wedge may be moved outwardly.

2. A wrench comprising a fixed jaw member having a shank, a movable jaw member slidably mounted on said shank, a wedge normally seated between and in engagement with said shank and movable jaw member to hold said members locked together, a spring bearing between said wedge and movable jaw to urge said wedge to remain seated, a

lever fulcrumed on said movable jaw, and a link connected to said lever and wedge whereby upon the rocking of said lever said wedge may be unseated.

In testimony whereof, I have hereunto set my hand, at Oakland, this 28th day of October, 1922.

FRANS D. FRANSON.
